INVENTOR

LUDWIG LEIN.

BY

Russell M. Everett,
ATTORNEY.

UNITED STATES PATENT OFFICE.

LUDWIG LEIN, OF ORANGE, NEW JERSEY.

TAILOR'S MEASURING DEVICE.

No. 839,302.

Specification of Letters Patent.

Patented Dec. 25, 1906.

Application filed May 21, 1906. Serial No. 317,864.

To all whom it may concern:

Be it known that I, LUDWIG LEIN, a citizen of the United States, and a resident of Orange, in the county of Essex and State of New Jersey, have invented certain new and useful Improvements in Tailors' Measuring Devices; and I do hereby declare the following to be a clear and exact description of said invention.

10 The invention relates more particularly to a measuring device by means of which the length of a lady's skirt can be exactly measured so that the bottom will hang evenly all around or lie in a plane parallel to the floor; 15 and the objects of my invention are to secure a separable standard and measuring-stick which combine to form a single measure; to secure a simple standard which shall afford a firm support for the device, while being cheap and easy to manufacture; to avoid 20 adjustments, thus securing greater accuracy, and to obtain other advantages and results, as may be brought out in the following description.

25 Referring to the accompanying drawings, in which like numerals of reference indicate corresponding parts in each of the several figures, Figure 1 is a plan of the standard for my improved measuring-gage. Fig. 2 is a 30 front view of the complete device in part section, and Fig. 3 is a side view of the device shown in position for measuring the bottom of a skirt or any drapery on said skirt.

It will be understood that it is difficult for 35 a tailor or dressmaker to properly gage the bottom of a skirt or get its edges in parallel relation to the floor unless by the use of some instrument. Furthermore, the instrument should rest in a very stable position

40 upon the floor without any tendency to be disturbed in its measuring relation to the skirt by being moved around, and there should be no parts which have to be adjusted to secure a measurement. These 45 features are all secured by my device, as shown in the drawings, wherein—

1 indicates a base or foundation constructed of wood and having its edges at two sides 2 and 3 and at one end 4 beveled or sloped. A 50 casting 5 is secured by a foot 6 to the base-board 1 by means of screws 7, passing through slots 9 in said foot. This casting provides an upright portion 8, which is of rectangular cross-section and cored out to form a socket 55 12 for a measuring-rod 19, said socket being

open at both ends. The casting 5 is so disposed upon the base 1 that one of the wide faces of the upright portion 8 lies flush with the unbeveled edge 10 of said base, the foot 6 projecting oppositely, as shown. A screw 60 11 in the base-piece 1 has its head projecting into the passage or opening 12 of said casting, and so coöperates with the screws 7 to secure the upright portion 5 firmly in position. The said socket 12 contains a removable 65 measuring-rod 19, having inches and subdivisions marked thereon in any usual manner, the first inch (marked "15,") being so located as to indicate not an inch from the end of the rod, but one inch from the floor or under surface of the base-piece 1. Furthermore, the outside of the upright portion 8 has marks or grooves 16, which exactly correspond with those of the stick, and the two parts form a single measure or scale. The lower end of 70 the rod 19 rests upon the top of the base 1 and is preferably recessed, as at 18, to receive the head of the screw 11.

A skirt 21 in the drawings shows how my device is employed to assist the dressmaker 80 in securing the proper height at all points at the bottom of said skirt accurately and easily. The device is stood on the floor close to the skirt and moved around to different points of the periphery thereof, and it should 85 be noted that in doing this there are no adjustments or changes of parts to affect the accuracy of the measuring. Furthermore, in moving the device from one position to another the beveled edges of the base insure a 90 downward pressure at the same time as a lateral movement, and danger of tipping the device or disturbing its measuring relation to the skirt is avoided.

Having thus described my invention, what 95 I claim as new is—

1. In a skirt-measuring device, the combination of a base-piece having a vertical edge, an upright portion flush at one side with said edge and having at its opposite side 100 a foot, said upright portion providing a socket open at the top, screws securing said foot to the base, and a measuring-rod removably inserted in said socket.

2. In a skirt-measuring device, the combination of a broad base-piece having one edge vertical and the others beveled, an upright portion mounted on said base-piece flush with said vertical edge, and a measuring-rod removably carried by said upright 110

portion, said beveled base being adapted to receive pressure to move the device laterally and at the same time prevent tilting.

3. In a skirt-measuring device, the combination of a base having a vertical edge, an upright tubular socket mounted upon said base with one side flush with said edge and having at the other side a slotted foot, holding-screws in said slots, a screw or the like projecting from the base upwardly into said socket, and a measuring-rod removably inserted in said socket.

4. In a skirt-measuring device, the combination of a base having a vertical edge, an upright tubular socket mounted upon said base with one side flush with said edge and having at the other side a slotted foot, hold-

ing-screws in said slots, a screw or the like projecting from the base upwardly into said socket, and a measuring-rod inserted in said socket and having its lower end recessed to receive said projecting member. 20

5. In a skirt-measuring device, the combination of a broad base having a vertical edge, an upright socket arranged flush with 25 said edge, and a measuring-rod removably inserted in said socket, graduations being provided upon both said rod and the socket which coöperate in measuring from the bottom of the base upward.

LUDWIG LEIN.
